PAGE 2

FIG. 2.

FIG. 3.

FIG. 4.

Figure 1 is a side elevational view of a ladder-truck body embodying my new design;

Figure 2 is a top plan view thereof;

Figure 3 is a rear end elevational view thereof; and Figure 4 is a perspective view thereof.

The opposite side to that shown in Figure 1 is substantially the same as the side shown. The dotted lines in the drawing are for illustrative purposes only.

I claim:

The ornamental design for a ladder-truck body, substantially as shown and described.
